UNITED STATES PATENT OFFICE.

DUNCAN McMILLAN, OF NEWARK, NEW JERSEY.

DESIGN FOR AN ASH-RECEIVER OR SIMILAR ARTICLE.

SPECIFICATION forming part of Design No. 30,936, dated June 6, 1899.

Application filed March 21, 1899. Serial No. 709,982. Term of patent 31 years.

To all whom it may concern:

Be it known that I, DUNCAN McMILLAN, a citizen of the United States, and a resident of Newark, county of Essex, and State of New Jersey, have invented and produced a new and original Design for an Ash-Receiver, of which the following is a specification, reference being had to the accompanying drawings, forming a part thereof, in which similar letters of reference indicate corresponding parts.

Figure 1 is a plan view of an ash-receiver, showing my design; and Fig. 2 is a longitudinal sectional elevation.

As shown in the drawings, the leading or material feature of my design consists in a circular end portion A and an elongated body B, extended laterally therefrom. The end portion is provided with a concavity or cup C and an angularly-extended annular wall D,

and the elongated body or portion B is provided with a longitudinally-extending groove E, angularly-extended side walls e, and a semicircular angularly-extended end wall e'.

It is apparent that my new design is also 25 applicable to cigar-rests, paper-weights, and other similar articles.

Having described my invention, what I claim as new, and desire to secure by Letters Patent, is—

The design for an ash-receiver or similar article, as herein shown and described.

In testimony that I claim the foregoing as my invention I have signed my name, in presence of two witnesses, this 20th day of March, 35 1899.

DUNCAN McMILLAN.

Witnesses:

M. G. MACLEAN,

GEO. E. BARRITT.
